DESIGN FOR A RADIATOR HUMIDIFIER

William Fader, Newark, N. J.

Application December 13, 1938, Serial No. 81,755

Term of patent 14 years

To all whom it may concern:

Be it known that I, William Fader, a citizen of the United States, residing at Newark, in the county of Essex and State of New Jersey, have invented a new, original, and ornamental Design for a Radiator Humidifier, of which the following is a specification, reference being had to the accompanying drawing, forming part thereof.

Figure 1 is a rear view in elevation showing my new design for radiator humidifier,

Figure 2 is an end view thereof,

Figure 3 is a top plan view thereof,

Figure 4 is a front elevational view thereof, and;

Figure 5 is a bottom edge view thereof.

The characteristic feature of my design resides in a humidifier of the specific configuration and arrangement of parts as shown.

I claim:

The ornamental design for a radiator humidifier, as shown and described.

WILLIAM FADER.
